(57) **CLAIM**

The ornamental design for a range, as shown and described.

DESCRIPTION

FIG. 1 is a perspective view of a range showing the new design, according to a first embodiment;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a perspective view of a range showing the new design, according to a second embodiment;

FIG. 8 is a front view thereof;

FIG. 9 is a right side view thereof;

FIG. 10 is a left side view thereof;

FIG. 11 is a top view thereof; and,

FIG. 12 is a bottom view thereof.

The broken lines shown are included for the purpose of illustrating environment or unclaimed portions of the article and form no part of the claimed design. The shading lines shown in the drawings represent the three-dimensional contour of the design, and are not intended to indicate surface decoration.

The rear views of the article are not part of the claimed design, and so the rear views have been omitted.
